INVENTOR

CHRISTIAN W.G. SODEMANN.

BY *James L. Hopkins*,
ATTY.

UNITED STATES PATENT OFFICE.

CHRISTIAN W. G. SODEMANN, OF ST. LOUIS, MISSOURI.

DESIGN FOR A RADIATOR-SHIELD.

48,507.

Specification for Design.

Patented Feb. 1, 1916.

Application filed September 13, 1915. Serial No. 50,512. Term of patent 3½ years.

To all whom it may concern:

Be it known that I, CHRISTIAN W. G. SODEMANN, a citizen of the United States, residing at 1512 Clark avenue, St. Louis, Missouri, have invented a new, original, and ornamental Design for Radiator-Shields, of which the following is a specification, reference being had to the accompanying drawing, forming part thereof.

The figure is a plan view of a radiator shield, showing my new design.

I claim:

The ornamental design for a radiator shield, substantially as shown.

CHRISTIAN W. G. SODEMANN.
